WATER SERVICE LINE CONNECTION

Burton Peters, Jr., 630 Edgevale Drive,
Erie, Pa. 16509

Filed Feb. 16, 1973, Ser. No. 332,784

Term of patent 14 years

Int. Cl. D23—01

U.S. Cl. D23—01

The figure is an isometric view of a water service line connection showing my new design.

The side of the article not shown is substantially the same as that which is shown.

The handle which is shown in broken lines is for illustrative purposes only and forms no part of the claim designed.

I claim:

The ornamental design for a water service line connection, as shown and described.
